(57) **CLAIM**

The ornamental design for an underwear garment with front flap, as shown and described.

DESCRIPTION

FIG. 1 is a front elevational view of an underwear garment with front flap showing my new design with the flap in a closed position;

FIG. 2 is a rear elevational view thereof;

FIG. 3 is a right side elevational view thereof, the left side elevational view being a mirror image thereof;

FIG. 4 is a bottom plan view thereof;

FIG. 5 is a top plan view thereof;

FIG. 6 is a front elevational view thereof shown with the flap in an open position;

FIG. 7 is a right side elevational view thereof, the left side elevational view being a mirror image thereof;

FIG. 8 is a bottom plan view thereof;

FIG. 9 is a top plan view thereof;

FIG. 10 is a perspective view of the underwear garment with front flap showing the flap in the closed position; and,

FIG. 11 is a perspective view of the underwear garment with front flap showing the flap in the open position.
